UNITED STATES PATENT OFFICE.

WILLIAM H. BUNCH, OF CONNELL, WASHINGTON.

ENGINE-STARTING MECHANISM.

1,150,742.

Specification of Letters Patent. Patented Aug. 17, 1915.

Application filed March 4, 1915. Serial No. 11,991.

To all whom it may concern:

Be it known that I, WILLIAM H. BUNCH, a citizen of the United States, residing at Connell, in the county of Franklin and State of Washington, have invented a new and useful Engine-Starting Mechanism, and I do hereby declare the following to be a full, clear, and exact description of the invention such as will enable others skilled in the art to which it appertains to make and use the same.

This invention relates to an improved starting mechanism for internal combustion engines, and an object of the invention is to provide a simple, efficient and practical device of this nature, in which a small internal combustion motor is utilized having its crank shaft coupled to another shaft which is provided with a pinion meshing 20 with a larger pinion carried by a shaft journaled in a frame, which is mounted to oscillate on the shaft of the pinion. The shaft on which the larger gear is loosely mounted, is provided with a friction wheel having 25 ratchet clutch connections with the larger gear, so that when revoluble motion is imparted to the larger gear, a corresponding movement is imparted to the friction wheel, which in turn frictionally imparts movement to the large fly wheel of a large motor or gas engine, that is, when the oscillatory frame is oscillated.

In practical fields the details of construction may necessitate alterations, falling 35 within the scope of what is claimed.

The invention comprises further features and combination of parts, as hereinafter set forth, shown in the drawings and claimed.

In the drawings:—Figure 1 is a view in 40 side elevation of a portion of a large gas engine, and illustrating the smaller and substantially two and a half horse power motor having connections with the large fly wheel of the gas engine for starting the same. Fig. 45 2 is a plan view of the starting mechanism as applied to the large fly wheel of the gas engine. Fig. 3 is a view in front elevation of the improved starting mechanism and the small motor, showing the large fly wheel in 50 the rear. Fig. 4 is an enlarged side elevation of the larger gear, showing parts in section and illustrating the clutch connections between the friction wheel or drum and the larger gear. Figs. 5 and 6 are detail views. 55 Referring more especially to the drawings, 1 designates a small internal combus-

tion motor provided with the usual fly wheel 2, and crank shaft 3, which shaft has a coupled connection 4 with a shaft 5. Secured at 6 to the foundation (on which the 60 gas engine structure and the motor structure 1 rest) are bearing brackets 7 and 8, and bolted upon the brackets by the bolts 9 are the bearing blocks 10, in which the shaft 5 is mounted, there being cap plates 11 to hold the shaft 5 in place, said plates being also bolted to the blocks by the bolts 9. Correspondingly shaped oppositely disposed levers 12 are provided, and their lower ends terminate in bearing blocks 13 having cap 70 plates 14 bolted thereto by the bolts 15. Between the bearing blocks 13 and the cap plates 14 the shaft 5 passes, therefore it will be observed that the levers 12 are pivotally mounted upon the shaft 5 so as to oscillate. 75 The upper ends of the levers 12 terminate in bearing blocks 16 having cap plates 17 bolted at 18, and mounted in said bearing blocks 16 and covered by the cap plates is a shaft 18, loosely on which is a gear 19, which 80 meshes with a smaller gear or pinion 20 mounted to rotate with the shaft 5. Keyed to rotate with the shaft 18 is a friction wheel or drum 21, the inner circumference of which at one end thereof is provided with 85 ratchet teeth 22. The outer periphery of the drum is preferably provided with a leather or other fiber covering 23, so as to increase the friction between the drum and the large fly wheel 24 of a large gas engine of conventional construction, as shown at 25. Pivotally mounted at 26 on a plate or disk 27 of the hub portion of the gear 19 are the spring retained pawls 28, which are designed to co-operate with the ratchet teeth 22 of the 90 drum, so that when the gear 19 is rotated the drum will revolve therewith, and when the drum is moved so that its fiber periphery will contact with the periphery of the fly wheel 24, the gas engine 25 will be operated 95 100 105 110

Pivoted at 30 to the bearing blocks 16, and converging toward each other are links 31, the converging ends of the links 31 are pivoted at 32 to the short arm 33 of the lever 34, which is pivotally mounted upon the shaft 35, which in turn is mounted in bearings of the frame 36. Pivoted at 37 to the lower part of a quadrant 38 is a lever 39 having a link connection 40 with the long arm 41 of said lever 34. It is to be noted that the lever 39 is provided with a dog 42 to engage

the teeth of the quadrant 38 to hold the lever 39 in adjusted position, there being a hand grip 44 for manipulating the dog, whereby the lever 39 may be adjusted. By moving 5 the lever 39 in the direction of the arrow α , the lever 34 will be oscillated upon its fulcrum, in turn oscillating the levers 12 through the medium of the links 31, thereby throwing the friction drum in contact 10 with the periphery of the fly wheel 24 of the gas engine, thereby starting the same, that is, subsequently to starting the small motor 1.

The invention having been set forth, what is claimed as new and useful is:—

- 15 In combination with a motor driven shaft provided with a gear, bearings for said shaft, a pair of correspondingly constructed oppositely disposed arms mounted upon said shaft to operate therewith, an auxiliary shaft 20 connecting the arms and mounted in bearings in the upper ends thereof, a gear loosely mounted upon the auxiliary shaft between the arms, a friction drum fixed to the aux-

iliary shaft between the arms, clutch means between the drum and the gear of the auxiliary shaft, which gear of the auxiliary shaft meshes with the first gear, a pair of links pivoted to the bearings of the upper ends of said arms and converging toward each other, a frame, an oscillatory lever pivoted in the frame having a short arm to which the converging ends of the links are connected and provided with a long arm, and means connected to the long arm for oscillating the oscillatory lever on its fulcrum, whereby the drum may be thrown into frictional contact with the fly wheel of a gas engine.

In testimony whereof I have signed my name to this specification in the presence of 40 two subscribing witnesses.

WILLIAM H. BUNCH.
